CHARLES H. WIGHT, OF BALTIMORE, MARYLAND.

Design No. 3,962, dated April 5, 1870; antedated March 19, 1870.

DESIGN FOR FRAME FOR CONTAINING STATIONERY ARTICLES.

The Schedule referred to in these Letters Patent and making part of the same.

To all whom it may concern.

Be it known that I, CHARLES H. WIGHT, of Baltimore, State of Maryland, have invented and produced a new and original Design for Stationery-Furniture, of which the following is a specification.

The nature of my design consists in providing suitable receptacles in a frame for the reception of a calendar, thermometer, letter-scales, stamp-safe, and ink-bottles or stands, and sponge-cup, as fully represented in the accompanying drawing.

What I claim as my invention is—

The design for stationery-furniture, herein described and shown in the drawing.

In testimony whereof I set my hand in presence of two witnesses.

CHARLES H. WIGHT.
